UNITED STATES PATENT OFFICE.

MORRIS P. BRAY, OF ANSONIA, ASSIGNOR TO WARNER BROS., OF BRIDGEPORT, CONNECTICUT.

DESIGN FOR THE ORNAMENTATION OF CORSETS.

SPECIFICATION forming part of Design No. 18,856, dated January 15, 1889.

Application filed October 29, 1888. Serial No. 289,470. Term of patent 14 years.

To all whom it may concern:

Be it known that I, MORRIS P. BRAY, of Ansonia, in the county of New Haven and State of Connecticut, have invented a new 5 Design for a Corset; and I do hereby declare the following, when taken in connection with accompanying drawing and the letters of reference marked thereon, to be a full, clear, and exact description of the same, and which said 10 drawing constitutes part of this specification, and represents a face view of one-half the corset.

This invention relates to a design for a corset, having for its object the ornamentation 15 of the exterior surface.

On the surface of the corset is the representation of a series of stripes running from top to bottom, the body showing a plain space between the stripes, the stripes themselves 20 each representing several vertical ribs, and the surface of each rib ornamented as shown. The ornamentation of the stripes, which extends throughout their length, is shown in full only near the ends, it being understood, 25 however, that the ornamentation is continued throughout the stripes. Combined with this

representation of vertical stripes is the representation of a transverse stripe, A, across the corset on the waist-line, the stripe represented as running straight from front to rear 30 and as underlying the vertical stripes. This straight transverse stripe is ornamented upon its surface, as shown in the accompanying illustration.

I claim—

The herein-described design for a corset, 35 consisting of the representation upon the body of the corset of vertical stripes, showing plain spaces between the stripes, the stripes each representing parallel ribs and the surface of 40 the ribs ornamented, combined with the representation of a straight stripe, A, running from front to rear on the waist-line and represented as passing inside the vertical stripes, the surface of the said straight stripe ornamented, all as shown in the accompanying 45 illustration.

MORRIS P. BRAY.
